[57] CLAIM

The ornamental design for a insect trap, as shown and described.

DESCRIPTION

FIG. 1 is a perspective drawing of the insect trap showing our new design in the closed position;

FIG. 2 is a perspective drawing of the insect trap in the open position thereof;

FIG. 3 is a back elevational view of the insect trap in the open position thereof;

FIG. 4 is a bottom plan view of the insect trap showing my new design in the closed position thereof;

FIG. 5 is a side elevational view of the insect trap in the open position, the opposite side being a mirror image thereof;

FIG. 6 is an inverted front elevational view of the insect trap in the open position thereof; and,

FIG. 7 is a top plan view of the insect trap in the open position.

FIG. 1

FIG. 2

FIG. 3

FIG. 4
